SCANNING CURRENT GENERATOR

Philo T. Farnsworth, San Francisco, Calif., assignor, by mesne assignments, to Farnsworth Television & Radio Corporation, Dover, Del., a corporation of Delaware

Application February 10, 1936, Serial No. 63,078

5 Claims. (Cl. 178—7.7)

This invention relates to generators for producing current waves of saw-tooth form in circuits containing both resistance and inductance, particularly as such circuits are used for the generation of scanning fields in oscillograph or cathode ray oscillograph tubes as used for television reception.

In my prior copending application, Serial No. 449,984, filed May 5, 1930, entitled "Television scanning and synchronizing system," I have shown that in order to produce such waves by means of thermionic amplifying tubes the control voltage applied to the grids of such tubes should be an extremely powerful pulse in one direction, so applied as to cause the sudden change of current from maximum to minimum (or from positive maximum to negative maximum) followed by a gradual and uniform change of voltage to produce a gradual straight-line rise of current from minimum to maximum. This wave form is necessary because the voltage necessary to overcome the inductive reactance of the circuit is directly proportional to the rate of change of current while the voltage necessary to overcome the resistance is proportional to the current itself. In the portion of the cycle where the current is changing from maximum to minimum the inductive component of the voltage is by far the larger, and hence the necessity for the powerful pulse. During the remainder of the cycle, where the rate of change of current is preferably not over two or three per cent as great as during the period of decreasing current, the inductive component of the voltage may be practically negligible, and the resistance component becomes dominant.

In the earlier copending application above referred to, a current wave of the desired form was passed through a distorting network in order to produce the desired voltage wave shape. The present invention relates to a method and means for using a succession of relatively short, widely spaced current pulses to produce the required wave form, these pulses being easily generated locally or derived from a received synchronizing pulse.

Among the objects of this invention are: to provide a means and method of generating saw-tooth waves of true straight-line form in an inductive-resistive circuit; to provide a means of generating such waves wherein the "fly-back time" is a very small part of the entire cycle; to provide a means of converting an oscillation consisting of short, widely separated current pulses into a saw-tooth wave; to provide a means of

generating a voltage pulse of the necessary amplitude to overcome the inductive reactance as required to secure an exceedingly short fly-back time; to provide a means of utilizing received or locally generated synchronizing pulses directly to produce saw-tooth waves, without the intervention of an electronic oscillator; and to provide a means of correcting the exponentially curved wave form which is derived from the discharge of a condenser to produce a true straight-line wave form.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

Considered broadly, this invention comprises suitable means for producing widely spaced short current pulses of the type above described, and a wave-forming network through which these pulses are passed. This network includes at least one parallel resistance-capacitance circuit which is connected in series with a simple resistor and a suitable source of current and voltage. In its limiting form such a pulse-generating oscillator will alternate between the condition wherein it forms an element of practically zero resistance in series with the wave-forming circuit just described and the current source, and a second condition wherein it forms an open circuit, and this theoretical condition can be quite nearly approached in practice. Means are provided for applying the voltage drop across the resistance-capacitance circuit and the resistor in series to an amplifier which is preferably non-linear. A sudden flow of current through the resistance element, when the oscillator is in the first or conducting condition, causes a voltage drop in the resistor which may be utilized as the pulse required to overcome the inductive reactants and cause the necessary rapid fly-back. This same current, flowing through the resistor in the resistance-capacitance circuit, imposes a charge upon the condenser in parallel therewith. When the second condition occurs all flow of current in the resistor ceases, and the only voltage remaining in the wave-forming circuit is that due to the charge upon the condenser. The discharge of this condenser causes the gradual

change of current desired for the second portion of the control-voltage cycle. The voltages thus produced are applied through a suitable network to control an amplifier having a non-linear characteristic, and these voltages are so applied that, considering equal small increments of time at the beginning and end of the cycle of condenser discharge, the relatively small changes of potential at the end of such cycle produce the same variations in current in the output of the amplifier as do the relatively large changes at the beginning of the cycle of condenser discharge.

It is to be understood that in speaking of the cycle of condenser charge and discharge, what is referred to is the degree of charge and discharge which are actually achieved by such condenser in the operation of the device, and that this cycle is relatively short compared with the time required for complete discharge of the condenser.

Referring to the drawings:

Figure 1 is a circuit diagram illustrating my invention as actuated by a "kipp-tube" oscillator.

Figure 2 is a series of curves showing the voltages and currents appearing in various portions of the circuit of Figure 1.

Figure 3 is a diagram of a modified form of circuit embodying the invention.

Figure 4 is a diagram of the circuit of the final stage of a television amplifier, showing the connection of the oscillating tube and the high- and low-frequency scanning-current generators.

Figure 5 is a diagram of the invention as applied to the high-frequency scanning circuit of a television receiver.

The operation of the system here disclosed can better be understood by reference to a preferred form of the device as shown in Figure 1. In this figure only the essential circuits are shown, the conventional filament-supply circuits being omitted for the sake of simplicity, since the methods of connecting such circuits are understood by all those skilled in the art. The pulse generator comprises a triode 1, which may conveniently be that type of thermionic tube marketed under the designation of "Type 56," and in the description which follows circuit constants will be given which are suitable for the generation of saw-tooth waves of from twenty to sixty cycles per second with a tube of this character, but it is to be understood that these constants are illustrative only, and that by varying them suitably both widely different frequencies may be generated and widely different types of tubes may be used, and that the changes necessary to accomplish this may readily be deduced from the values given by the use of well-known engineering principles.

The cathode 2 of the tube 1 is shown as grounded. The grid 3 is connected through the secondary winding 5 of a small transformer to a timing circuit comprising a condenser 6, which may have a capacitance of the order of 0.25 microfarad, in parallel with a variable resistor 7 whose maximum resistance is conveniently of the order of 250,000 ohms, and thence to ground. The plate or anode 8 of the tube 1 connects through the primary winding 10 of the above-mentioned transformer to the wave-forming circuit, which includes the pulse resistor 11 and an integrating circuit 12 comprising a resistor 13 of the order of 200,000 ohms in parallel with a condenser 15 of the order of 0.5 microfarad.

The circuit as thus described may be connected

directly in series with the usual plate-current supply 16 and thus to ground, but I prefer to include in series therewith a resistor 17 of the order of 50,000 ohms and a by-pass condenser 18 having a capacitance of the order of 20 to 30 microfarads. The condenser 18 is primarily intended as a bypass, but its effect for this purpose is substantially unimpaired by the presence of the series resistor 17 and the combination has substantially the same effect as would increasing somewhat the time constant of the integrating circuit 12.

The operation of the circuit as thus far described is as follows: When the device is put into operation there is no bias upon the grid 3 and current passes in the plate circuit, including the transformer primary winding 10. This induces a voltage in the secondary winding 5 of this transformer (which preferably has a step-up turns ratio of about 1.5 to 1), the transformer being so poled that increase of current in the primary winding swings the grid positive. This not only causes an increased flow in the plate circuit but also causes current flow to the grid, until charging of the condenser 6 and the collection of the negative charge upon the grid causes the current to start to diminish. This at once tends to swing the grid negative, due to the action of the transformer, and causes a complete blocking of the tube which persists until the charge leaks off of the condenser 6 through the resistor 7, whereupon the cycle repeats. The curves 20 and 21 of Fig. 2 show the approximate waveform of the plate and grid currents, respectively. The time required for the charge to leak off of the condenser 6 is controlled by varying the resistor 7, and is, in practice, much longer than would be indicated by the curves, the ratio of the length of the current pulses to the interval between such pulses being in practice from $\frac{1}{30}$ to $\frac{1}{40}$. The voltage on the grid 3 of the tube 1 is shown in like manner by the curve 22 of Figure 2.

The current I_p , as shown in curve 20, flowing in the integrating circuit 12, causes a voltage drop across the condenser 15 as shown by the falling portion of curve 23, and onto this voltage drop is superposed the drop caused by the flow in the resistor 11. This gives a voltage during the period of flow which is shown by that portion of curve 25 between the origin O and the ordinate A. At this point the current suddenly ceases to flow, and curve 23 illustrates the rise of voltage during the period of discharge of condenser 15. The curve for this period of discharge is nearly straight, being slightly convex upward.

Curve 25 shows the final form of the voltage wave as it is applied to the amplifier, as will next be described. The voltage between the plate end of the wave-forming network and ground is applied across the input or control circuit of an amplifier through a network which comprises a blocking condenser 30 having a capacitance of about 1.0 microfarad, in series with two resistors 31 and 32 of a value of about 250,000 ohms each, which form a voltage divider.

The output amplifier, which is connected across the resistor 32, comprises in the present instance two more type 56 tubes, 35 and 36, whose plates 37 and 38 are connected in push-pull relationship across a deflecting magnet 40, which is illustrated merely as an iron-core coil. The center tap of this magnet connects through the lead 41 to the supply source 16.

The grid 42 of the tube 35 is connected to the

junction of the resistors 31 and 32, and the filament or cathode 43 of this tube connects to ground through a resistor 45 of about 1000 ohms. The filament 46 of tube 36 is also connected to ground through this resistor, whereas the grid 47 connects directly to ground.

As a result of this asymmetrical connection the two tubes are unequally biased and loaded. The major portion of the control voltage is applied 10 across tube 35, whose grid swings positive during a part of the cycle and therefore acquires a bias through the resistor 32. Additional bias is supplied to both tubes through the resistor 45. The unbalanced connection of the tubes and the un- 15 equal application of voltage to them results in a curvature of the grid-plate characteristic of the two tubes considered as a unit, and this is in opposition to the curvature of the discharge characteristic of the condenser 15. It is difficult, 20 however, to get an exact balance in this manner, and the final correction may be applied by connecting two similar small condensers 49 and 50 across the resistors 31 and 32. The proper size for these condensers can speedily be found 25 by experiment, but will be of the order of 0.05 microfarad.

In connection with the action of these condensers, it is appropriate to consider the functioning of the entire coupling network during the 30 various parts of the cycle. The complete solution of this network involves expressions which are so complex as to obscure what actually takes place, but it is possible to break down the circuit into its component elements and so to obtain an ap- 35 proximate picture of what happens. It should be noted first that the frequency of the oscillation is dependent almost entirely on the relationship between the condenser 6 and the resistor 7, and that the effect of the coupling circuit upon the 40 oscillation period may be neglected. It should also be noted that the circuit is quite different during the current pulses and in the interval between the pulses.

The pulse period itself is so short in compari- 45 son with the time constant of the various circuit elements that the condensers 15, 18 and 30 can be entirely neglected and thought of as replaced by direct metallic connection. Condensers 49 and 50 in series may therefore be considered as 50 forming one arm of a parallel circuit whose other two arms are respectively the pulse resistor 11 and the resistors 31 and 32 in series. Because of the relatively high resistance of the elements 31 and 32, they too may be neglected and the pulse 55 may be considered as supplied through the resistor 11 (2,000 to 5,000 ohms) in parallel with the capacitance of 0.025 microfarad. The time constant of such a combination is of the order of 5×10^{-5} , which is so small that even in the short- 60 est fly-back time contemplated in this arrangement, the pulse voltage is reduced by much less than one per cent by the presence of these condensers.

When the tube 1 becomes non-conductive the 65 dominant elements in the network are the integrating circuit 12, which has a time constant of approximately 0.1 and a branch comprising the condenser 30 and the resistors 31 and 32 with their shunting condensers. Considering only the 70 resistors and the condenser 30 in series, the time constant of this combination is about 0.5, which is so long in comparison with that of the integrating circuit that the presence of the condenser 30 may, as a first approximation, be neglected together with the resistance 11, and the network

considered as one wherein the source 16 is in series with the integrating circuit and a circuit comprising the resistors 31 and 32 shunted by a condenser whose capacitance is that of condensers 49 and 50 in series.

Conditions at any time during the portion of the cycle when the tube is non-conducting are those which may be computed by considering that a short circuit across this latter branch of the circuit has suddenly been removed. The 10 solution of this circuit shows it to be in the form $1 - ke^{-at}$. The presence of the small condensers 49 and 50 decreases both k and a ; that is, it reduces slightly the amplitude of the voltage variations as applied to the amplifier and increases 15 the time constant of the circuit, straightening the curve. The decrease in amplitude is relatively slight for small values of capacitance, but the increase in time constant is of sufficient magnitude to be of material value when applied as a 20 final correction. In the second approximation, wherein the effect of the series condenser 30 is considered, the complete solution is very complex, but the over-all effect is again an effective increase in time constant, straightening the curve 25 still further with a slight decrease in amplitude. The final curve of voltage rise across the amplifier may be made as straight as desired, but it is preferable practically to leave some curvature in the applied voltage curve and to apply a small 30 but definite positive correction by means of the amplifier characteristic as above described. With the constants above given the departure from linearity thus to be corrected is less than 1.5 per cent at a frequency of 24 cycles, and is en- 35 tirely negligible at a frequency of 60 cycles.

The saw-tooth oscillator thus described is self-oscillatory with considerable stability, but it may readily be synchronized by injecting a small voltage of the desired frequency into the transformer 40 which couples the grid and the plate circuit of the tube 1. This may be done by an additional small winding 51 coupled to the transformer core and fed from any desired source.

Figure 3 shows a form of the invention which 45 is primarily adapted for use with television transmitters where it is desirable to have the frequency absolutely controlled by external mechanical means. The short, widely separated positive pulses are fed to a tube 61, which is normally 50 biased to cutoff, through the lead 62. The output circuit of the tube 61 is similar to that of the embodiment first described, and the circuit elements are designated by the same reference characters distinguished by primes. It is as- 55 sumed, however, that the tubes 35' and 36' are tubes of low amplification factor and high current-carrying capacity. In order to obtain the necessary amplification the tube 35' is therefore used to drive the tube 36' through a circuit 60 comprising a large blocking condenser 63 in series with a resistor 65, which connects to the grid 47' and to ground through a resistor 66. This connection gives greatly increased amplification, particularly of the pulse, and the pulse 65 resistor 11' can therefore be reduced in size. The biases on the tubes 35' and 36' will usually have to be somewhat different from those shown in the embodiment of Figure 1 in order to get the desired corrective asymmetry of the grid-plate 70 characteristic of the amplifier, but this is dependent upon the particular tubes used.

One of the most important features of my invention is that this type of circuit permits the synchronizing pulses sent out by the transmitter 75

to be utilized directly to effect scanning without the intervention of any kipp tube or local oscillator whatsoever.

As has been shown in my copending application Ser. No. 449,984, and as is now the universal practice in electronic television systems, a pulse sent out between each two lines of scan, and another transmitted between each two picture frames, may be utilized for the dual purpose of holding the receiver in step and of eliminating the back lines in the received picture. Figure 4 shows the method of applying the present invention to accomplish this directly. The combined pulses and picture signals, amplified to the required degree by any convenient type of amplifier 70, are fed through a blocking condenser 71 to the control grid of a final power tube 72 which further amplifies the signals and applies them through a blocking condenser 74 to the grid of the oscillight 75, the output of the amplifier 70 being so phased that the synchronizing pulses comprise positive swings as applied to the grid of the power tube, by which they are reversed in phase and applied as negative swings to the oscillight, erasing the back lines.

The tube 72 is provided with the usual grid leak 76. Also connected to the grid is a resistor 77 to which the high-frequency and low-frequency scanning units are connected through a pair of conjugate filters, the high-frequency unit connecting to the resistor 77 through a small condenser 79, with a resistor 80 as a shunt element across the scanning generator input, while the low-frequency unit is preferably connected through a series resistor 81 with the condenser 82 as the shunt element. The output of the high-frequency unit 83 connects to a set of high-frequency scanning coils 84, while the output of the low-frequency scanning unit 85 connects to the low-frequency deflecting coil 86. The circuits of the scanning units 83 and 85 differ essentially only in their circuit constants, and hence only the high-frequency unit 83, as shown more completely in Figure 5, will be described in detail.

Referring to Fig. 5, the positive synchronizing pulse which appears across the shunt resistor 80 is applied to the grid 90 of a triode 91, whose cathode 92 is self-biased almost to cutoff by a resistor 94, a large by-pass condenser 95 being shunted across this resistor to maintain the cathode at ground potential insofar as alternating-current components are concerned. The plate of the tube 91 is connected through a pulse resistor 96 and integrating circuit 97, operating as has already been described, to a source of plate potential indicated by B+. The positive pulses render the tube 91 instantaneously conducting, and the pulses charge the integrating circuit 97, as has already been described, to develop the desired wave form. For this particular use, however, where light weight and simplicity are paramount factors, the simplest type of network is used to couple the succeeding amplifier, in this case simply a blocking condenser 99 and grid resistor 100, of the order of magnitude of 2.0 microfarads and 100,000 ohms, respectively, transferring the saw-tooth wave to a heater-type tube 101. This tube is parallel-fed through a plate reactor 102, its output circuit being through another blocking condenser 104, also preferably having a capacitance of about 2.0 microfarads, and a variable resistor 105, having a maximum resistance of about 200 ohms, to the two high-

frequency scanning coils 84 whose combined inductance is about 2.6 millihenries.

In this case the wave form applied to the tube 101 is not as highly corrected as in the embodiments previously described, but since a single 5 amplifier tube is used its plate characteristic will have somewhat greater curvature, so that satisfactory linearity of wave form may be obtained. The final adjustment of this linearity is made by varying the resistance of the element 105. 10

This same type of high-frequency scanning circuit has also been used for transmitters, but whereas for receiver scanning units a single amplifier tube of the 2A3 type, for example, may be used, for the transmitters several of these tubes 15 will be used in parallel.

Where this type of circuit is used for the low-frequency scanning, the constants of the pulse resistor and integrating circuit will be of about the same magnitude as those of the first embodiment described, instead of using an integrating circuit with a time constant of about 0.0005 as in the high-frequency unit. The blocking condenser 99 will have the same value as in the high-frequency unit, but the grid leak 100 will be two to three times as great in resistance. The plate reactor 102 and blocking condenser 104 will also be much larger, and I have also found it more convenient to use a type 2A5 output tube than the 2A3 which has proved most satisfactory 30 thus far in the high-frequency units. All of these modifications for change in frequency are, however, exactly what would be expected from ordinary engineering considerations, and many other variants of the system will naturally suggest themselves to designers in the art. Furthermore, it will be apparent that where the oscillight is sufficiently sensitive to control voltages the phase-reversing amplifier may be used in cascade with the scanning generators instead of with the 40 oscillight, the primary requirement being merely that the pulses be applied to the oscillight and generators in opposite phase. 35

I claim:

1. The method of producing synchronized saw-tooth scanning waves in reactive scanning circuits in a receiver for television signals which include pulses adapted to extinguish return lines in the received picture, which comprises the steps of amplifying said pulses with reversal of phase so that said pulses appear with opposite signs in different portions of said receiver, applying said pulses in one phase to cause current flow in one portion of said receiver, producing a distorted voltage wave from said current flow of proper form to produce a saw-tooth wave in a circuit containing reactance, applying such saw-tooth wave to scan a picture field, and applying said pulses simultaneously in opposite phase to suppress flow in another portion of said receiver. 50

2. The method of producing synchronized saw-tooth scanning waves in reactive scanning circuits in a receiver for television signals which include pulses adapted to extinguish return lines 65 in the received picture, which comprises the steps of amplifying said pulses with reversal of phase so that said pulses appear with opposite signs in different portions of said receiver, applying said pulses in positive phase to cause current flow, distorting and amplifying said current flow to produce a scanning wave, and simultaneously applying said pulses in negative phase to suppress a current flow to extinguish the return lines in the received picture. 70

3. The method of producing synchronized saw-tooth scanning currents in an inductive and resistive scanning circuit in a receiver for television signals which include pulses adapted to extinguish return lines in the received picture, which comprises the steps of amplifying said pulses with reversal of phase so that the pulse appears in different portions of said receiver with opposite signs, applying said pulse in positive phase to cause a current flow in said scanning circuit substantially coincident therewith in duration, applying a potential in phase with said pulse to cause a sudden change of said current flow, limiting the subsequent changes of current in said scanning circuit to a substantially constant rate until again changed by a pulse, and applying said pulses in negative phase to extinguish the return lines simultaneously with said sudden change.
4. A receiver for television signals which include pulses adapted to extinguish return lines in the received picture, comprising means for amplifying said pulses with reversal of phase
- so that said pulses appear with opposite signs in different portions of said receiver, means for applying said pulses in one phase to cause current flow in one portion of said receiver, means for producing a distorted voltage wave from said current flow of proper form to produce a saw-tooth wave in a circuit containing reactance, means for utilizing such saw-tooth wave to scan a picture field, and means for applying said pulses simultaneously in opposite phase to suppress flow in another portion of said receiver.
5. A television signal receiving system comprising scanning circuits adapted to be actuated by a scanning wave of saw-tooth wave form, means for receiving a synchronizing signal comprising pulses corresponding in time to the desired periodicity of said scanning wave, an amplifier for said signal, means coupled to said amplifier for distorting the amplified pulses to develop therefrom a saw-tooth scanning wave, and means for utilizing said scanning wave to actuate said scanning circuits.

PHILO T. FARNSWORTH.
